CLAIM

The ornamental design for a truck for carrying goods,
as shown and described.

DESCRIPTION

FIG. 1 is a perspective view of a truck for carrying
goods showing my new design;

FIG. 2 is a top plan view thereof;

FIG. 3 is a right side elevational view thereof, the left
side being a mirror image of the right side;

FIG. 4 is a front elevational view thereof;

FIG. 5 is a rear elevational view thereof;

FIG. 6 is a bottom plan view thereof; and,

FIG. 7 is a right side elevational view thereof showing
the table at a lower level for receiving goods.

FIG. 1FIG. 2FIG. 4FIG. 3
